STOOL

Alice L. Turnbull, Vienna, Va.

Application February 9, 1950, Serial No. 7,834

Term of patent 14 years

(Cl. D15—8)

To all whom it may concern:

Be it known that I, Alice L. Turnbull, a citizen of the United States, residing at Vienna, in the county of Fairfax and State of Virginia, have invented a new, original, and ornamental Design for a Stool, of which the following is a specification, reference being had to the accompanying drawing, forming part thereof.

Fig. 1 is a side perspective view of a stool showing my new design;

Fig. 2 is a top plan view;

Fig. 3 is a side elevational view; and

Fig. 4 is a front elevational view of my stool.

I claim:

The ornamental design for a stool, as shown.

ALICE L. TURNBULL.
